FUEL CONDITIONING DEVICE

Wesley T. Rhoten, Miamiville, Ohio

Application November 20, 1945, Serial No. 629,874

2 Claims. (Cl. 261—91)

1

This present invention relates to fuel conditioning devices wherein gasoline or heavier liquid fuels are acted upon to produce such a condition of the fuel as will be suitable for its use in internal combustion engines.

The main object of the invention is the provision of a carburetor in which the fuel is vaporized by suction and the vapor is mixed with air to the saturation point and the mixture is conducted to the motor.

Another object of the invention is the creation of the vacuum by centrifugal force.

With the above and other objects in view the invention consists of certain novel details of construction and combination of parts hereinafter fully described and claimed.

In the drawings forming part of this specification and illustrating the following description:

Figure 1 is a diametral section of the preferred embodiment of my invention;

Figure 2 is an enlarged detail section through a part of a spraying conduit and the jet at the outer end thereof;

Figure 3 is a transverse section on line 3—3 of Figure 1;

Figure 4 is an enlarged transverse section on line 4—4 of Figure 1;

Figure 5 is a detail perspective view of a fragmentary pipe forming part of the withdrawal conduit.

Fig. 6 shows in section the impeller structure by which fuel is elevated.

Referring more particularly to the drawing in which like characters of reference designate like or similar parts throughout the several views, 2 indicates a gasoline chamber a vertical wall of which has a tubular extension 3. A pipe 4 supplying gasoline is inserted through the extension and is held therein by a nut 5. The inner end of the pipe within the chamber is closed by a valve member 7 which is hinged at its lower edge by a pin 8 to the inner side of the chamber and rigid with a float member 9, if the level of the gasoline in which the float member floats is sufficiently high. If the level drops the valve is automatically opened.

The gasoline chamber has a horizontal flange 10 at its upper edge and is fastened by bolts 11 passing through the flange and the bottom of a main casting 13 to the latter. The circular bottom of the

2

substantially cylindrical casing is centrally apertured at 15 to permit the insertion of a cylindrical withdrawal sleeve 17, the axis of which is vertically disposed. The exterior cylindrical surface of the sleeve is sufficiently spaced from the concave edge of the opening to establish communication between the chamber and casing.

The lower end portion of the sleeve is immersed in the gasoline and surrounds a tube 19 which is provided at its lower end by a cylindrical cap 20 having an aperture in its flat bottom (Fig. 6). A ball 21 is seated on the aperture and permits gasoline to enter the pipe, but prevents its outward flow. The cap carries at its lower end an impeller structure 23 which includes a cylinder closed at both ends and an apertured cylindrical wall 24. Gasoline may enter through openings in such wall into four spaces each bounded by the concave surface of one vane 25 and the convex surface of another vane. These spaces communicate through openings 27 with the interior of an inner cylinder 28 which opens at the top into the ball covered aperture (Fig. 6).

The tube is fastened at its upper end in the center of the top 31 of a bottomless revolvable drum 32 which is divided by four partitions 33 into an equal number of sectoral chambers. The top end of the drum has a central enlargement or boss 35 which is tapped for insertion of the lower threaded end of a shaft 37 journaled in a bearing 38. The same is mounted in a recess formed in the enlarged central part of the top 40 of the main casing. Bolts 41 secure the former to the latter.

The shaft is rigid with and driven by the armature of a motor 43 bolted by bolts 44 to the segmental portions of a pair of angle brackets 46 also including vertical parts 47 and horizontal flanges 48. The latter are secured by bolts 41 to the top surface of the top of the casing.

The upper end of the tube 19 has a plurality of holes each of which registers with a radial conduit 50 formed in the top end of the drum and communicating by a nozzle or jet 51 with one of the drum chambers. Each nozzle has an upper threaded portion for insertion in a tapped hole in the drum top (Figs. 1, 2).

In the cylindrical wall of the casing and to the right of the drum is an oblique hole 54 registering with a hole in a stand or air intake pipe 55 which is connected at its upper end to an air filter

(not shown) and attached to the main casing. Below the holes described is another pair of registering holes in the casing and stand pipe. A branch pipe 56 extends from and connects to the withdrawal sleeve 17 through the lower hole in the casing wall into the hole of the stand pipe. A slotted piece of pipe 58 of the diameter of the branch pipe also extends into the lower hole in the stand pipe and abuts against the end of the branch pipe. This fragmentary pipe has the lower half of its intermediate portion cut away and extends with its complete right-hand end portion into an exteriorly threaded plug 59 which is received into a hole in the stand pipe and carries a lock-nut 60.

The slotted piece of pipe can be set at different angles for different fuel-and-air ratios.

A throttle 62 has the form of a circular disc of a diameter equal to the inner diameter of the stand pipe. This disc is secured along a diameter to a pair of pivot trunnions 63 rotatably mounted in the stand pipe. The right-hand trunnion extends to the right side of the stand pipe and may be used as a handle for adjusting the extent of the throttle opening.

Gasoline or other fuel enters the chamber to the extent permitted by the float and fills the lower end of the tube carrying the ball valve and impeller and is lifted in liquid form by the rotation of the same and fills in such form the rest of the tube and the radial conduits 50 in the drum top. Rotation of the tube and the impeller carried by the lower end thereof will sweep liquid gasoline into the lower end of the tube after lifting the valve ball to replace the lifted liquid gasoline. Rotation of the drum with the tube will develop centrifugal forces which cause the liquid gasoline to move outwardly in the radial conduits so that suction takes place and aids the lifting of the liquid gasoline in the bottom portion of the tube. The rotation of the impeller at the lower end of the tube keeps the lower part thereof filled with liquid gasoline.

The centrifugal force moves the liquid gasoline in the radial conduits outwardly and through the nozzles at the outer ends thereof in sprayed form into the chamber where the heavier particles are thrown against the inner side of the cylindrical walls of the chamber. Then they fall back to the bottom of the casing and from there into the gasoline.

The lighter particles however are picked up by air entering the withdrawal sleeve after readily mixing with the air admitted into the space above the sleeve. The mixture reaches a saturation point and any gasoline vapor left after this point is reached will condense and fall to the bottom like the heavier particles.

When the withdrawal increases less pure gasoline vapor will fall to the bottom, because more of such vapor will mix with the additional air drawn in. The mixture in the withdrawal sleeve and branch pipe will therefore not exceed the saturation point.

I am aware that the particular embodiment of my invention above described and illustrated in the accompanying drawing is susceptible of considerable variations without departing from the spirit thereof, and therefore I desire to claim my invention broadly as well as specifically as indicated by the appended claims.

What I claim as new and desire to protect by Letters Patent of the United States is as follows:

1. In combination, an air intake pipe having a throttle valve therein, a main casing associated

with the air intake pipe and having an opening near to its top communicating with a corresponding opening of the air intake pipe at a point above the throttle valve, a revolvable drum having radially inwardly extending fins disposed in the main casing with its outer wall extending below the opening of the main casing with the air intake pipe, rotatable means on the casing for revolving the revolvable drum, said revolvable drum having a top portion with radially outwardly extending conduits therein, the outer ends of these conduits communicating with the interior of the drum, chamber means containing liquid fuel connected to the bottom of the main casing, a central pipe extending down from the top portion of the revolvable drum and communicating with the radial conduits thereof and adapted to enter the liquid fuel to cause the liquid fuel to be raised as the drum is rotated and distributed to the radial conduits thereof, whereby liquid fuel will be delivered to the outlets of the radial conduits and to the interior of the drum, a withdrawal sleeve surrounding the central pipe and spaced therefrom to receive air and fuel mixture formed within the revolvable drum from air entering the main casing from the air intake pipe and drawn upwardly into the space within the revolvable drum from its bottom opening thereof, a branch pipe extending from the withdrawal sleeve into the air intake pipe at a point between the air inlet to the main casing and the throttle valve, and outlet means in the bottom of the main casing for returning such heavy particles of the fuel which have not mixed with the air to the fuel chamber, the lower end of said withdrawal sleeve communicating with the liquid fuel chamber to extract such heavy particles of fuel which have not mixed with the air from the mixture.

40 with the air from the mixture.

41 2. In combination, an air intake pipe having
a throttle valve therein, a main casing associated
with the air intake pipe and having an
opening near to its top communicating with a
corresponding opening of the air intake pipe at
45 a point above the throttle valve, a revolvable
drum having radially inwardly extending fins
disposed within the main casing with its outer
wall extending below the opening of the main
casing with the air intake pipe, rotatable means
50 on the casing for revolving the revolvable drum,
said revolvable drum having a top portion with
radially outwardly extending conduits therein,
the outer ends of these conduits communicating
55 with the interior of the drum, chamber means
containing liquid fuel connected to the bottom
of the main casing, a central pipe extending
down from the top portion of the revolvable
drum and communicating with the radial con-
duits thereof and adapted to enter the liquid
60 fuel to cause the liquid fuel to be raised as the
drum is rotated and distributed to the radial
conduits thereof, whereby liquid fuel will be de-
livered to the outlets of the radial conduits and
to the interior of the drum, a withdrawal sleeve
65 surrounding the central pipe and spaced there-
from to receive air and fuel mixture formed with-
in the revolvable drum from air entering the
main casing from the air intake pipe and drawn
upwardly into the space within the revolvable
70 drum from its bottom opening thereof, a branch
pipe extending from the withdrawal sleeve into
the air intake pipe at a point between the air
inlet to the main casing and the throttle valve,
and outlet means in the bottom of the main cas-
ing for returning such heavy particles of the fuel

which have not mixed with the air to the fuel chamber, the lower end of said withdrawal sleeve communicating with the liquid fuel chamber to extract such heavy particles of fuel which have not mixed with the air from the mixture, a pipe having an opening extending from one side thereof rotatably mounted in said air intake pipe and having one end in axial communication with the branch pipe connected with the withdrawal sleeve, said pipe being adjustable about its longitudinal axis, means exteriorly disposed of the air intake and connected with the pipe for effecting a rotational adjustment of the pipe within the air intake, and means for locking the pipe and its adjustable means in their adjusted 15 positions.
